DIFFERENTIAL CYLINDER-PISTON
ASSEMBLY

John Adams Thierry, South Milwaukee, Wis., assignor to Bucyrus-Erie Company, South Milwaukee, Wis., a corporation of Delaware

Application May 23, 1947, Serial No. 749,921

20 Claims. (Cl. 60—97)

1

My invention relates to new and useful improvements in double-acting differential cylinder-piston assemblies, specifically those of the type that utilize fluid by-pass grooves on the surface of the piston and/or cylinder to effect one or more changes in the force-speed ratio of the assembly at different stages of relative travel of the piston and cylinder.

The principal object of my invention is to provide an improved by-pass type double-acting differential cylinder-piston assembly, in which:

- (1) The cylinder chamber is no longer than the length of the piston stroke (plus the piston thickness).
- (2) The cylinder chamber is of uniform cross-section for its entire length.
- (3) The piston is short, and of simple solid construction.
- (4) A minimum of fluid by-pass grooves are employed.
- (5) No enclosed longitudinal fluid passages are required.
- (6) No special constrictions are required on the inner surface of the cylinder to change the force-speed ratio.
- (7) The force-speed ratios are substantially the same for travel in either direction at any portion of the stroke.
- (8) Assembly and disassembly is simple.
- (9) Cost of manufacture is reduced.

My invention consists in the novel parts and in the combination and arrangement thereof, which are defined in the appended claims, and of which one embodiment is exemplified in the accompanying drawing, which are hereinafter particularly described and explained.

Throughout the description the same reference number is applied to the same member or to similar members.

Figures 1 to 3 inclusive each constitute a longitudinal section of my invention, the piston assembly being shown in three successive positions, from lowest to highest, with respect to the cylinder assembly which is fixed.

Figure 4 is a plan view of the piston assembly, taken along the line 4—4 of Figure 1.

Referring now to Figures 1 to 3, we see that the interior of outer main cylinder 11 is divided by inner auxiliary cylinder 12 into main chamber 13 and auxiliary chamber 14; main chamber 13 being the space between these cylinders, and having a greater cross-sectional area than auxiliary chamber 14.

For ease in manufacture and assembly, the main and auxiliary cylinders preferably have a common bottom 15, but separate tops 16 and 17

2

respectively. Top 16 fits partly over and around top 17 of auxiliary cylinder 12 to hold it in place.

Fluid port 18 in bottom 15 leads into auxiliary chamber 14, and fluid port 19 in top 16 leads into main chamber 13.

My piston consists of main piston 20 which has fluid-tight sliding contact with the inside of main cylinder 11 and the outside of auxiliary cylinder 12, and auxiliary piston 21 which has fluid-tight sliding contact with the inside of auxiliary cylinder 12. Extending upwardly from main piston 20 are preferably two piston rods 22 which extend out through fluid-tight openings in top 16 of main cylinder 11. Extending upwardly from auxiliary piston 21 is piston rod 23 which passes out through a fluid-tight opening in top 17. Piston rods 22 and 23 are preferably located in the same vertical plane and are connected outside the assembly to the end 20 of a single rod 24 which is preferably aligned with inner rod 23. Likewise pistons 20 and 21 are preferably aligned to lie in the same horizontal transverse plane. Stops 25 at each end of pistons 20 and 21 prevent the ends of the pistons from abutting the ends of the cylinders.

On the inside of the walls enclosing main chamber 13 (preferably on the inside surface of main cylinder 11) there are lengthwise grooves 26; and on the inside surface of auxiliary cylinder 12 there are lengthwise grooves 27. Grooves 26 and 27 are located at ends of these respective chambers that are opposite to the ends in which are located fluid ports 18 and 19 into these chambers.

Fluid ports 28 at the lower end of grooves 27 in auxiliary cylinder 12 provide a passage between chambers 13 and 14.

Grooves 26 inside main cylinder 11, grooves 27 inside auxiliary cylinder 12, and ports 28 through auxiliary cylinder 12 are so positioned relative to each other that grooves 26 will bypass around piston 20 if and only if grooves 27 are blocked from by-passing around auxiliary piston 21, and vice versa, and that when the piston of one chamber is by-passed, the internal port functions as the pressure inlet of said other chamber whenever fluid is admitted under pressure to said one chamber through its external port, and as the exhaust port of said one chamber whenever fluid is admitted under pressure to said other chamber through its external port; and that when the piston of said one chamber is no longer by-passed, the internal port functions as the exhaust port of said one chamber whenever fluid is admitted under pressure through the external port of said one chamber,

and as the pressure inlet of said one chamber whenever fluid is admitted under pressure through the external port of said other chamber. The relative length of each set of grooves is determined by the relative length of travel for each of the speeds which they produce.

It will be seen from the foregoing description of my invention that I have in effect two pistons operating in two respective cylinders. That is to say, my main piston 20 operates in a main chamber 13 the walls of which are the inner surface of my main cylinder 11 plus the outer surface of auxiliary cylinder 12, and my auxiliary piston operates in an auxiliary chamber 14 the walls of which are the inner surface of auxiliary cylinder 12.

It will be noted that my auxiliary piston 21 and its cooperating auxiliary chamber 14 have a smaller effective pressure-area than that of my main piston 20 and its main chamber 13.

The operation of my cylinder-piston assembly is as follows:

Assume the apparatus to be in the position shown in Figure 1. Pressure fluid is admitted, through port 18, into the lower end of the auxiliary chamber 14, just below auxiliary piston 21, setting up pressure against the cross-sectional area of this piston. Under the influence of this pressure, piston 21 and its piston-rod 23 move upwardly rapidly with slight force, carrying with them main piston 20 and its piston-rods 22.

Meanwhile, exhaust from the upper end of auxiliary chambers 14 passes through ports 28 into main chamber 13; pressures above and below main piston 20 are equalized through grooves 26, and exhaust from the upper end of main chamber 13 passes out through port 19 at the top of the cylinder.

Turning now to Figure 3, when pistons 20 and 21 have reached the position shown in this figure, piston 21 has uncovered port 28 and hence fluid is now free to pass through ports 28 into the lower portion of main chamber 13, setting up pressure against the lower face of main piston 20 around which fluid is no longer free to pass. Since pressures above and below auxiliary piston 21 are equalized through grooves 27, the effective pressure area now becomes the area of the face of main piston 20, which is considerably more than the area of the face of auxiliary piston 21. Accordingly pistons 20 and 21 and their rods 22 and 23 now move upwardly slowly with considerably greater force than in the first portion of the stroke. Exhaust from the upper end of main chamber 11 passes out through port 19 at the top of the cylinder.

Figure 2 shows the assembly with the pistons in the intermediate position just as they pass from the high to the low-speed portions of their travel.

The reverse motion (downward) is similar, the initial and final pressure being against the upper instead of the lower faces of pistons 20 and 21 respectively. Fluid under pressure is admitted, through port 19, into the upper end of main chamber 11, and the exhaust from the lower end of auxiliary chamber 12 passes out through port 18. Now, however, the travel is slow and forceful at the beginning of the travel, and is fast and less forceful at the end of the travel. Both speeds are slightly higher and less forceful than the corresponding speeds of the upward stroke, due to the piston rods which reduce slightly the effective pressure area of the pistons.

Having now described and illustrated one form

of my invention, I wish it to be understood that my invention is not to be limited to the specific form or arrangement of parts herein described and shown.

5 Thus, it will be evident that, although I have shown, as a typical embodiment of my invention, a two-speed differential cylinder-piston assembly using two concentric cylinders and two concentric pistons, nevertheless my invention is not to be so limited, being equally applicable to assemblies employing any number of concentric cylinders and pistons to produce a like number of speeds, the external ports leading always preferably to the innermost and outermost chambers.

10 Furthermore, it will be readily seen that the by-pass grooves in a chamber (such as chamber 13 of by-pass 1 to 3) between walls formed by the inner surface of one cylinder and the outer surface of another cylinder, may be located on either wall without affecting the operation of the assembly, and my claims are to be so interpreted.

I claim:

1. In a cylinder-piston assembly, the combination of: a main cylinder having a main chamber 25 with main piston therein of relatively large effective pressure-area; an auxiliary cylinder inside and conterminous with the main cylinder and having an auxiliary chamber with an auxiliary piston therein of relatively small effective pressure area; a piston rod; means operatively connecting the two pistons to the piston rod; means for alternatively admitting fluid under pressure to the main chamber or to the auxiliary chamber, and for simultaneously permitting exhaust from the other chamber; means for automatically bypassing fluid past one of the pistons whenever the piston-rod is near one end of its stroke; and means for automatically bypassing fluid past the other piston at another stage of said stroke.

2. A cylinder-piston assembly, according to claim 1, further characterized by the fact that one or another of the by-pass means is always blocked.

3. A cylinder-piston assembly, according to claim 1, further characterized by the fact that the by-pass means for the main piston includes at least one longitudinal groove in a wall of the main chamber, which groove is uncoverable by relative motion of the piston-rod and the main cylinder.

4. A cylinder-piston assembly, according to claim 1, further characterized by the fact that the by-pass means for the auxiliary piston includes at least one longitudinal groove in a wall of the auxiliary chamber, which groove is uncoverable by relative motion of the piston-rod and the auxiliary cylinder.

5. A cylinder-piston assembly, according to claim 1, further characterized by the fact that the by-pass means for the auxiliary and main pistons includes respectively at least one longitudinal groove in the interior surface of the auxiliary cylinder and at least one longitudinal groove in the exterior surface of the auxiliary cylinder.

6. A cylinder-piston assembly, according to claim 1, further characterized by the fact that the means operatively connecting the two pistons to the piston-rod includes: a piston-rod connected to the auxiliary piston; a piston rod connected to the main piston; and means connecting the two last-mentioned piston rods to the first-mentioned piston rod.

7. A cylinder-piston assembly, according to claim 1, further characterized by the fact that the main and auxiliary pistons lie in substantially

the same plane transverse to their direction of travel.

8. A cylinder-piston assembly, according to claim 1, further characterized by the fact that the main cylinder is substantially the same length as the stroke of the piston-rod relative thereto.

9. A cylinder-piston assembly, according to claim 1, further characterized by the fact that the main and auxiliary cylinders are concentric, and their respective chambers are connected by a fluid port in the wall of the auxiliary-cylinder.

10. A cylinder-piston assembly, according to claim 1, further characterized by the fact that whenever the by-pass means of one piston bypasses said one piston, the by-pass means of the other piston will not by-pass said other piston.

11. A cylinder-piston assembly, according to claim 1, further characterized by the fact that the means for admitting fluid under pressure to the main and auxiliary cylinders includes: an external port at one end of the main chamber; an external port at the opposite end of the auxiliary chamber; and an internal port providing passage between the main and auxiliary cylinders so positioned that: when the piston of one chamber is by-passed, the internal port functions as the pressure inlet of said other chamber whenever fluid is admitted under pressure to said one chamber through its external port, and as the exhaust port of said one chamber whenever fluid is admitted under pressure to said other chamber through its external port; and that when the piston of said one chamber is no longer by-passed, the internal port functions as the exhaust port of said one chamber whenever fluid is admitted under pressure through the external port of said one chamber, and as the pressure inlet of said one chamber whenever fluid is admitted under pressure through the external port of said other chamber.

12. In a cylinder-piston assembly, the combination of: a main cylinder and an associated auxiliary cylinder of lesser diameter; a main piston having outwardly a sliding contact with the interior surface of the main cylinder and the exterior surface of the auxiliary cylinder; an auxiliary piston having outwardly a sliding contact with the interior surface of the auxiliary cylinder; a piston-rod operatively connected to the main and auxiliary pistons; and a system of fluid conduits providing a by-pass past the area of contact between the main piston and one of the cylinders, and a by-pass past the area of contact between the auxiliary piston and its cylinder, these by-passes being opened and closed automatically by the relative motions of the pistons and cylinders, and being so positioned that whenever one by-pass is open the other by-pass is closed.

13. A cylinder-piston assembly according to claim 12, further characterized by the fact that the system of fluid conduits includes at least one longitudinal groove in the interior surface of the main cylinder, which groove is uncoverable by relative motion of the piston rod and the main cylinder.

14. A cylinder-piston assembly according to claim 12, further characterized by the fact that the system of fluid conduits includes at least one longitudinal groove in the interior surface of the auxiliary cylinder, which groove is uncoverable by relative motion of the piston rod and the auxiliary cylinder.

15. A cylinder-piston assembly, according to claim 12, further characterized by the fact that the system of fluid conduits includes respectively at least one longitudinal groove in the interior

surface of the auxiliary cylinder and at least one longitudinal groove in the exterior surface of the auxiliary cylinder.

16. A cylinder-piston assembly, according to claim 12, further characterized by the fact that the main and auxiliary pistons lie in substantially the same plane transverse to their direction of travel.

17. A cylinder-piston assembly according to claim 12, further characterized by the fact that the main and auxiliary cylinders are concentric, conterminal, and substantially the same length as the stroke of the piston-rod relative to the main cylinder.

18. A cylinder-piston assembly according to claim 12, further characterized by the fact that the system of fluid conduits includes: an external port at one end of the main cylinder chamber; an external port at the opposite end of the auxiliary cylinder chamber; and an internal port providing passage between the main and auxiliary cylinder chambers so positioned that: when the piston of one chamber is by-passed, the internal port functions as the pressure inlet of said other chamber whenever fluid is admitted under pressure to said one chamber through its external port, and as the exhaust port of said one chamber whenever fluid is admitted under pressure through the external port of said one chamber, and that when the piston of said one chamber is no longer by-passed, the internal port functions as the exhaust port of said one chamber whenever fluid is admitted under pressure through the external port of said one chamber, and as the pressure inlet of said one chamber whenever fluid is admitted under pressure through the external port of said other chamber.

19. In a cylinder-piston assembly, the combination of: a main cylinder and an associated auxiliary cylinder of lesser diameter; a main piston having outwardly a fluid-sealed sliding contact with the interior surface of the main cylinder and the exterior surface of the auxiliary cylinder; an auxiliary piston having outwardly a fluid-sealed sliding contact with the interior surface of the auxiliary cylinder; a piston-rod operatively connected to the main and auxiliary pistons; means for the introduction of pressure-fluid into the cylinders, to actuate relative reciprocation of the pistons in one direction; means for the introduction of pressure-fluid into the cylinders, to actuate relative reciprocation of the pistons in the other direction; by-pass means, to break the fluid seal between the main piston and one of the cylinders, automatically rendered effective by the relative position of the piston and said one of the cylinders during a part of the relative reciprocation of the main piston in each direction, and automatically rendered ineffective by the relative position of the main piston and said one of the cylinders during another part of the relative reciprocation of the main piston in each direction; bypass means to break the fluid seal between the auxiliary piston means and its cylinder, automatically rendered effective by the relative position of the auxiliary piston and its cylinder during a part of the relative reciprocation of the auxiliary piston in each direction, and automatically rendered ineffective by the relative position of the auxiliary piston and its cylinder during another part of the relative reciprocation of the auxiliary piston in each direction; whereby the main piston is relieved of fluid pressure and the auxiliary piston is subjected to fluid pressure during a portion of the reciprocation in each di-

rection, and the auxiliary piston is relieved of fluid pressure and the main piston is subjected to fluid pressure during another portion of the reciprocation in each direction.

20. A cylinder-piston assembly according to claim 19, further characterized by the fact that the by-pass means that functions to break the fluid seal between one of the pistons and one of the cylinders comprises at least one duct extending from one point on the surface of said one of the cylinders to another point thereon longitudinally spaced from the first point, said duct being

5

effective when these two points bracket said one of the pistons, and ineffective when these two points do not bracket said one of the pistons.
